UNITED STATES PATENT OFFICE.

STEVE NAGY, OF DELRAY, MICHIGAN.

WHEEL TOY.

Specification of Letters Patent.

Patented Mar. 31, 1914.

1,091,950.

Application filed July 3, 1913. Serial No. 777,158.

To all whom it may concern:

Be it known that I, STEVE NAGY, a subject of the King of Hungary, residing at Delray, in the county of Wayne and State of Michigan, have invented certain new and useful Improvements in Wheel Toys, of which the following is a specification, reference being had therein to the accompanying drawing.

10 This invention relates to wheel toys and has for its object to provide in a manner as hereinafter set forth, a portable body provided with a plurality of miniature figures adapted to be operated when the body is 15 propelled thereby affording considerable amusement.

Further objects of the invention are to provide a wheel toy which is comparatively simple in its construction and arrangement, 20 strong, durable, affording considerable amusement to a child when operated and comparatively inexpensive to manufacture.

With the foregoing and other objects in view, the invention consists of the novel 25 construction, combination and arrangement of parts as hereinafter more specifically described and illustrated in the accompanying drawings, wherein is shown an embodiment of the invention, but it is to be understood that changes, variations and modifications 30 stood that changes, variations and modifications can be resorted to which come within the scope of the claims hereunto appended.

In the drawings wherein like reference 35 characters denote the corresponding parts throughout the several views, Figure 1 is an elevation of a wheel toy in accordance with this invention looking at one side thereof, Fig. 2 is a like view looking toward the 40 other side thereof, Fig. 3 is a top plan, and Fig. 4 is an inverted plan.

Referring to the drawings by reference characters, 1 denotes a platform provided with longitudinally extending depending 45 members 2, 3 and in which is journaled a rear axle 4, connected to a king bolt 5 in the front axle 6. Wheels 7 are carried by the front and rear axle. Mounted upon the king bolt 5 and interposed between the front 50 axle 6 and platform 1, is a fifth wheel 8 to which is connected a shaft or handle 9. Attached to the fifth wheel 8 is a double tree 10, which is connected to the projecting ends 11 of the front axle 6 by the coupling members 12.

The platform 1 at the rear thereof is pro-

vided with a longitudinally extending slot 13 through which depends a cog wheel 14, carried by a spindle 15 which is rotatably secured in the bearing brackets 16, 17 upon the upper face of the platform 1. The spindle 15 projects from the bracket 17 and has attached thereto a series of radially disposed flags 18. The cog wheel 14 is fixed to the inner end of the spindle 15 and projecting from the inner end of the spindle 15 is a crank shaft 19, which is connected to and reciprocates an actuating bar 20. Secured to one side of the platform 1, is a support 21 provided at its top with an anvil or representation of an anvil as indicated at 22. Arranged at each side of the support 21 are longitudinally extending members 23 between which extend miniature figures 24, 25 and by way of example, each 75 of these figures is a representation of a blacksmith. Each of the figures is pivotally mounted upon a pin 26 supported by the members 23 and the said members 23 are fixedly secured as at 27 to the support 30 21. The figure 24 is pivotally connected at its lower end to the bar 20, inwardly with respect to the rear end of said bar and the figure 25 is pivotally connected at its lower end as at 29 to the forward end of said bar. 35 Each of the figures 24, 25 is provided with a pair of arms 30 and secured to each pair of arms is the handle 31 of a sledge 32. The figures are so arranged with respect to the anvil 22 and operated through the medium 90 of the bar 20 as to cause the sledges 32 to alternately engage the anvil 22.

The cog wheel 14 is operated by a circular row of spaced pins 33 carried by a pair of spaced disks 34 fixed to the axle 4. The 95 teeth of the cog wheel 14 extend down into the spaces between the pins 33 so that when the axle 4 is revolved, when the platform 1 is pulled over a surface, the disk 34 will revolve carrying the pins 33 therewith and these pins successively engage the teeth of the cog wheel 14. The spindle 15 will be revolved carrying the crank shaft 19 therewith, reciprocating the bar 20, alternately 100 rocking the figures 24, 25 in opposite directions upon their pivots, causing thereby the alternate striking of the anvil by the sledge 32, or if not the anvil the imitation of the object to move upon the anvil and in the path of the sledges.

105 Rotatably mounted upon the platform 1 is a vertically disposed rotatable member 35

provided with a groove 36 through which travels an endless belt 37, the latter passing through a groove 38 provided in the periphery of the spindle 15. By this arrangement, 5 when the spindle 15 is rotated, the belt 37 will be shifted causing thereby the rotation of the member 35. Mounted upon the member 35 is a miniature figure 39 carrying the representation of a bar or other object 40 10 which is adapted to be positioned upon the anvil 22 after each complete revolution of the member 35 and be struck by one of the sledges 32 as clearly shown in Fig. 2.

The object 40 is alternately struck by the 15 sledges 32. Mounted upon the forward end of the platform 1 is a seat 41 in which is mounted a miniature figure 42 to represent a driver. The body of the figure 42 is pivotally connected as at 43 and has one end of 20 a spring 44 connected thereto. The other end of the spring is attached to the back of the seat 41 and the function of said spring 44 is to maintain the body 42 upright. The body 42 is rocked on its pivot by a member 25 45 which is attached to the body 42 and pivoted as at 46 to a support 47. The member 45, which is termed an actuating member has its lower end attached to a link 48 connected to one end of a pivoted dog 49 which 30 is engaged by a ratchet wheel 50 carried by the member 35. When the member 35 is rotated, the wheel 50 is carried therewith and has the teeth thereof intermittently engaged with the dog 49, the latter is oscillated reciprocating the link 48, oscillating the member 45 upon its pivot and shifting the body 42 in an oscillatory manner upon its pivot 43. The shifting of the body 42 forwardly 35 is had against the action of the spring 44.

40 The figures 24, 25, 39 and 42 are operably connected in such a manner that they will operate in unison.

What I claim is:

1. A figure wheel toy comprising a portable body, a stationary support thereon provided with a representation of an anvil, a rotatable member adapted to position an object upon said anvil, a pair of oscillatory elements provided with the representation of sledges to alternately strike said object, and means driven from the moving portable body for operating said member and said element.
2. A figure wheel toy comprising a portable body, a stationary support thereon provided with a representation of an anvil, a rotatable member adapted to position an object upon said anvil, a pair of oscillatory elements provided with the representation of sledges to alternately strike said object, and means driven from the moving portable body

for operating said member and said element, an oscillatory member arranged at the forward end of said body, and means driven from said rotatable member for imparting an oscillatory movement of the member arranged at the forward end of the body. 65

3. A figure wheel toy comprising a portable body, a stationary support provided with the representation of an anvil, a pair of oscillatory elements suspended from said support and each provided with the representation of a sledge, a reciprocatory means connected to said elements for alternately operating them in opposite directions, driving means for said reciprocatory means, said driving means operated from a moving part of said body, a rotatable member provided with an object adapted to be positioned upon said anvil after each complete revolution of said member, and an operative connection 70 between said member and said driving means 80 for rotating said member.

4. A figure wheel toy comprising a portable body, a stationary support provided with the representation of an anvil, a pair of oscillatory elements suspended from said support and each provided with the representation of a sledge, a reciprocatory means connected to said elements for alternately operating them in opposite directions, driving means for said reciprocatory means, said driving means operated from a moving part of said body, a rotatable member provided with an object adapted to be positioned upon said anvil after each complete revolution of 85 said member, an operative connection 90 between said member and said driving means for rotating said member, and an oscillatory element arranged at the forward end of said body, driven from said rotatable member 100 and constitutes a representation of a driver.

5. A figure wheel toy comprising a portable body, a support carried thereby, and provided with a representation of an anvil, oscillatory members provided with a representation of sledges adapted to alternately engage said anvil or an object thereon, rotatable means for positioning an object upon said anvil, an oscillatory element arranged at the forward portion of said body and constituting the representation of a driver, and means driven from the moving part of said body for operating said oscillatory elements and member in unison. 105 110

In testimony whereof I affix my signature 115 in the presence of two witnesses.

STEVE NAGY.
